UNITED STATES PATENT OFFICE.

ROSS F. WORKMAN AND MYRTLE WORKMAN, OF YORK, PENNSYLVANIA.

FASTENING AND HOLDING DEVICE.

1,369,513.

Specification of Letters Patent. Patented Feb. 22, 1921.

Application filed June 4, 1920. Serial No. 386,420.

To all whom it may concern:

Be it known that we, ROSS F. WORKMAN and MYRTLE WORKMAN, citizens of the United States, residing at York, in the 5 county of York and State of Pennsylvania, have invented certain new and useful Improvements in Fastening and Holding Devices; and we do hereby declare the following to be a full, clear, and exact description 10 of the invention, such as will enable others skilled in the art to which it appertains to make and use the same.

This invention relates to a fastening device for engaging and holding the tip or 15 free end of a shoe lacing or other small article. The principal object of our invention is to provide a fastening device of simple construction, adapted to be invisibly attached to the upper part of a shoe for ret- 20 ceiving and gripping the metal or other tip of a lacing, or to be attached in other positions for holding small articles.

A special object is to provide a lacing tip-holder, cut or stamped from sheet metal 25 and having a body or eye forming portion, spring arms or prongs to form a holding socket, and an upper mouth provided with clencher teeth or claws to secure the device in the leather or a trimming part of a 30 shoe, the device being preferably concealed between the outer leather and the lining, or other trimming part.

We preferably make a single-piece blank, cut or stamped from sheet metal, contain- 35 ing all the parts of our device, and then shape it up into the form of the finished article.

The matter constituting our invention will be defined in the claims.

40 We will now describe the details of construction by reference to the accompanying drawings, in which—

Figure 1 represents an elevation of the fastener showing the clencher teeth or 5 claws applied to the top of a shoe.

Fig. 2 represents a detached side elevation taken at right angles to the view shown in Fig. 1.

Fig. 3 represents a top plan of the view 50 shown in Fig. 1.

Fig. 4 represents a flat face view of the blank of sheet metal from which the device is formed.

Fig. 5 represents a central vertical sec- 55 tion of the device attached as shown in Fig. 1.

While we have shown in the drawings our fastening and holding device applied to a part of a shoe, we wish it understood that it is not limited in use to such particular 60 application, but may be applied to other apparel for gripping and holding small articles.

The fastening and holding device 1 is preferably made from spring sheet metal, 65 such as copper, cut in the form of a blank, Fig. 4. The blank is bent and shaped to form a tubular spring body or eye 2, hav- 70 ing at one end a mouth 7 provided at the edge with the clenching teeth or claws 3, 75 of which there may be two or more, but preferably three, as shown. The portion 2 is preferably provided at its opposite end with two longitudinal spring arms or prongs 4, 4^a, which will be opposite each other, 80 leaving a space 5 between them in the finished article. The body or eye 2 and prongs 4, 4^a form a spring socket adapted to grip and hold an article, such as a lacing tip or other article when inserted therein. This 85 device does not require a special holding pocket, but may be inserted directly between folds of material, such as the outer leather and the lining or a trimming part of a shoe, or between folds of fabric in any desired 90 position or part of a garment. In the finished article the clenching teeth 3 may be left straight and flat as indicated in Fig. 4, or may be bent approximately at right angles to the body 1, as shown in Fig. 2. At 95 the time of applying the device to a shoe or other article of apparel the teeth will be bent inward and slightly curled or turned upon themselves after passing through a fold of leather or fabric, as shown in Fig. 95

5, so as to securely attach and hold the device in place. When the body portion 2 of the blank is bent into tubular form the side edges are preferably caused to abut one another, rather than overlap, so as to 100 provide an expansible spring holder and make a neat finish. The teeth 3 will be nearly or quite in a semi-circle and will thus better grip the leather or fabric and slightly crimp it to better hold the spring prongs 105 against sidewise or swinging movement. The mouth end of the body 2 is provided with a short projection 6 which may be slightly turned outward to form a guide-way or bell-mouth 7 to facilitate the inser- 110 tion of a string tip or other article in the holder.

The device will preferably be inserted at the upper edge or seam of a shoe top between the outer leather and the lining so that the two prongs 4, 4^a shall lie flat 5 against the material, as indicated in Fig. 5, thereby causing pressure upon them and aiding their gripping action. The prongs, however, may be made sufficiently strong and resilient to firmly grip and hold a 10 string tip or other article in place. The teeth 3 may be placed either at the inside or the outside of a shoe top, and when clenched will be barely visible.

This device can be variously modified in 15 details of construction within the spirit and scope of our invention. For instance, the prongs may be transversely curved, or may be transversely corrugated or otherwise roughened on their inner surfaces, as by indentations or punctures made in their outer surfaces. The prongs may be wider and the spaces 5 narrower than shown in Fig. 20 4, but for the sake of economy the prongs of one blank may be cut by a die from the metal where the spaces 5 appear, thus cutting 25 two blanks by one stroke of the die, and thereby saving time and material.

The prong 4^a is preferably made as an extension of the body portion 1, its outer edge 30 being in line with the outer edge of said body portion, and the prong 4 is also made as an extension of the portion 1, but at an offset 1^a from the opposite edge of the blank, Fig. 4, and so as to have a space 5 substantially 35 the width of a prong between the prongs 4—4^a, the offset is also substantially the width of a prong. This is our preferred construction of the blank for the sake of economy in the use of material, but our invention is not limited to such details of 40 construction.

The device, being made of thin sheet metal, occupies only a very narrow space and in no way mars the appearance of a 45 shoe or an article of apparel; it is quite effective and satisfactory in use.

Our device has the advantage of having a 50 double spring action. The tubular socket or guide is yieldable so as to take any size tip and grip the same firmly, thereby forming a circular spring. This tubular guide may be tapered slightly which makes it

easier to insert in the incision made just below the top stitching of the shoe upper. The prongs 4—4^a besides gripping the tip 55 serve to guide the same to its place when inserting it; they are to be rounded at the lower end.

Having described our invention, what we claim, and desire to secure by Letters Patent, is:—

1. A fastening device of the character described, comprising an elastic solid tubular body or eye portion having at the edge of one end attaching means and at its other end 65 spaced spring prongs to form a holding socket.

2. A fastening device of the character described, comprising a solid expansible tubular body portion, provided at the edge of one end with clenching teeth and at the opposite end with longitudinal spring prongs, adapted to grip and hold an article inserted between them.

3. A fastening and holding device, comprising a tubular spring gripping socket having at one end longitudinal spring prongs and at the other end clenching teeth in line with the wall of said socket and adapted to be passed through a fabric and 75 then turned inward and upon themselves.

4. A sheet metal blank for a fastening and holding device having a plain body forming portion, clenching teeth at one edge thereof and longitudinal spaced spring 85 prongs projecting from the opposite edge to form a holding socket.

5. A sheet metal blank of resilient material for making a fastening and holding device having a plain body forming portion 90 provided at one edge with clenching teeth, and at the opposite edge with longitudinal prongs having a space between them of substantially the same width as one of the prongs, whereby economy may be effected in cutting the blanks.

In testimony whereof, we affix our signatures.

ROSS F. WORKMAN.
MYRTLE WORKMAN.
